US00D641797S

(12) **United States Design Patent**
Chen

(10) **Patent No.:** **US D641,797 S**
(45) **Date of Patent:** **** Jul. 19, 2011**

(54) **GAME CONTROLLER**

(75) Inventor: **Chih-Chung Chen**, Tu-Cheng (TW)

(73) Assignee: **Cheng Uei Precision Industry Co., Ltd.**, Tu-Cheng, Taipei Hsien (TW)

(**) Term: **14 Years**

(21) Appl. No.: **29/376,061**

(22) Filed: **Sep. 30, 2010**

(51) **LOC (9) Cl.** **21-01**

(52) **U.S. Cl.** **D21/333; D14/400**

(58) **Field of Classification Search** ..... **D21/324, D21/328, 333, 385, 477, 566; D14/399-402, D14/412, 414, 416, 432; 273/148 B, 449, 273/441, 442; 463/1, 29-35, 46, 47; 345/156, 345/161; 434/45, 46**

See application file for complete search history.
